CHECK-PROTECTING MACHINE.

1,333,106.

Specification of Letters Patent.

Patented Mar. 9, 1920.

Application filed June 3, 1918. Serial No. 237,967.

To all whom it may concern:

Be it known that I, BENJAMIN O. FANSLOW, a citizen of the United States, residing in White Plains, county of Westchester, 5 and State of New York, have invented a new and useful Improvement in Check-Protecting Machines, of which the following is a description.

This invention relates to check protecting 10 machines, and, particularly, to the type thereof known as check-writers and to the further type thereof wherein the movements imparted to the printing-wheel are produced by a plunger-twirler.

15 Among the objects of my invention may be noted the following: to provide a check protecting machine with means whereby the printing-wheel may be locked in functional or printing position during the printing 20 movement imparted thereto, said means being simple, durable, strong and economical to produce; to provide a printing-wheel locking means in part carried by the printing-wheel supporting means and in part by 25 a stationary or rigid part of the machine; to provide means by which the printing-wheel and pointer are held together for coöperative action and which insures the positive rotation of the pointer with the printing- 30 wheel; to provide means by which the printing-wheel is held snugly against the front of the machine at all times whereby the printing impression will be regular, uniform and positive, regardless of the line of type or 35 type-block which may be set for impression purposes; to provide a combination of means by which the check may be printed and fed through the machine toward the operator so that each impression made immediately be- 40 comes visible and is brought into full view of the operator; and to provide certain de- 45 tails of construction which are strong, simple and durable for supporting and actuating the printing-wheel for its various functional purposes.

In order that my invention may be clearly understood, I have provided drawings wherein:

Figure 1 is a front elevation showing a

form of check-writer embodying my invention;

Fig. 2 is a sectional view of the machine taken substantially on the line 2—2, for example, of Fig. 3;

Fig. 3 is a sectional view taken substantially on the line 3—3 of Fig. 1; and

Fig. 4 is a view similar to Fig. 3 showing the parts in a different position.

Referring to the drawings, the numeral 1 indicates the bed of the machine and 2 the frame or housing for the various operating mechanisms. The frame 2 is, or may be, cast or formed in one piece and is so shaped as to provide at the bottom thereof at opposite ends a rib 3 and channel 4 for the co-operation of correspondingly formed ends of the bed 1, the structure being such that the frame 2 is supported upon the bed 1, while the latter, at its ends, is entirely covered by the frame. At back and front, the frame 2 is provided with members 5, the outer surfaces of which are rounded and the inner surfaces of which are flat and inclined so as to coöperate with correspondingly formed front and back surfaces of the bed, this structure making a close, strong and neat fit between the bed and the frame. The bed and frame are held together by a plurality of screws 6 extending through the bottom of the bed and into the rib 3 of the frame at its opposite ends. The frame 3 is so formed just above the upper surface of the bed as to provide a passage for the check through the machine, slots 7 at front and back of the frame giving free passage to the check and also being sufficiently large to receive a pair of check-guides, the bases 8 of which are provided with one or more lugs 9 operating in a groove 10 extending longitudinally of the bed in its upper surface at its back, just within the back of the frame, see Figs. 2, 3, and 4. The check-guides are arranged on opposite sides of the platen 11 and may be shifted along said grooves to positions enabling them to engage the opposite edges of the check to be printed. The guiding member 12 of the check-guides is U-shaped and said member extends from

back to front of the machine. The check-guides are each provided with an upwardly extending member 13 by which the same may be manipulated and also with an upturned tongue 14 for facilitating the entry of the check into the guide. The platen 11 is secured in any suitable manner to the bed 1, which, for its reception, is provided with a slot 15 in its upper surface in which the platen may be adjusted so as to properly place the same for coöperation with the type-blocks on the printing-wheel. The upper surface of the platen, as also the surfaces of the type-blocks, is preferably provided with a plurality of points or projections and depressions which, when brought together upon the opposite surfaces of the check, macerate the fiber so as to enable it to readily absorb the ink spread upon the surface of the type-blocks, this being done by breaking, disrupting, or otherwise disfiguring the fiber of the check, without literally cutting through or cleanly separating the fiber.

25 In order to protect the surface of the desk or table upon which the machine is set, the bed 1 is provided with a mat 16, which may be of rubber, felt, or other soft material calculated to both protect the desk 30 surface and deaden the sound of the operation of the machine. The mat also has the function of covering the heads of the screws 6, which secure the bed and frame together.

Within the frame, and considerably above the bed, two oppositely disposed and quite substantial webs 17 are provided, in each of which a channel or guideway 18 is formed, the function of which is to guide the opposite edges of the cross-head, carrier or plunger 19 from which extends vertically the spindle 20, the upper end of which is screw-threaded, as at 21, and on which is threaded the nut 22 operating as supporting and holding means for the handle 23, by which the plunger or cross-head 19 is manipulated. The spindle 20 extends through the sheath 24, which is recessed at its upper end for the reception of the coiled spring 25, which surrounds the spindle 20, and the upper end of which spring engages the nut 22 whereby to normally hold the handle 23, spindle 20, and cross-head 19 in elevated position, as shown in Figs. 1, 2 and 3. The spindle 20 is connected at its 55 lower end to a bevel-gear 26, which operates through a slot 27 in the plunger 19, the handle 23 thus also having the function of rotating or twirling the spindle 20 and the bevel-gear 26. The plunger 19 is provided with the laterally extending, hollow hub or barrel 28, which extends toward the front of the frame and which is surrounded by the hub 29 of a bevel-gear 29^a which meshes with the bevel-gear 26, said hub 60 being externally screw-threaded for the re-

ception of the internally screw-threaded web of the printing-wheel 30, see Figs. 3 and 4. The printing-wheel has any desired number of type surfaces or blocks 31, Fig. 2, upon which the words are formed, and 70 which coöperate with the platen 11. The outer end of the hub 29 has secured thereto, by means of screws 33, the internally screw-threaded ring 32, receiving the screw-threaded end of the hub 34 of the pointer 75 35, which is located outside the front of the frame and the hub of which operates in the elongated slot 36 in said frame. The surface of the front of the frame is dialed, as at 37, the indicia being arranged circularly 80 so as to coöperate with the pointer 35 when the same is twirled. The barrel 28 houses a spring 38 which operates to force a pin 39 outwardly against the end of the hub 34 of the pointer, thus normally pressing the hub 85 outwardly, together with the ring 32, hub 29 of the bevel-gear, and the printing-wheel 30, the latter being provided with a flange 40, which engages a smooth plate 41 suitably secured to the inner surface of the front 90 of the frame of the machine. Inasmuch as the inner surface of the front of the frame may be uneven or be somewhat rough, resulting in retarding the movement of the printing-wheel when it is desired to rotate 95 the same and also during its reciprocating movement, the smooth plate 41 is interposed between the inner surface of the frame and the surface of the flange 40, thus enabling the printing-wheel to have a perfectly 100 smooth, uniform and flat surface to rotate and reciprocate against, the spring 38 normally yieldingly holding the printing-wheel against said plate 41 and insuring also the proper coöperation of the type-blocks 105 with the platen. Moreover, the bevel-gear carried by the hub 29 is maintained properly in mesh with the gear 26 without binding or slipping. Thus the handle 23 is enabled to positively rotate the printing-wheel 110 in opposite directions and likewise drive the same into printing position.

It is essential that the printing-wheel be positively and firmly locked during the printing operation so as to prevent a type-block, after being set for a printing operation, from shifting out of coöoperative relation with the platen. To prevent such shifting, a positive locking mechanism is employed consisting of a fixture 42 having 115 an underbent member 43 secured to the bottom of one of the webs 17, so that its bifurcated arm or extension 44 may be held rigidly in position to receive between its prongs the rear end 45 of a lever fulcrumed 120 at 46 between a pair of lugs 47 on the bottom of the plunger 19 just above the inner surface of the printing-wheel 30. The forward end 48 of the said lever is extended 125 into position to coöperate with a plurality 130

of circumferentially arranged ribs or lugs 49 carried on the inner surface of the printing-wheel 30, said extension 48, in order to lock the printing-wheel from movement, 5 being projected between a pair of said lugs as the printing-wheel is moved into printing position. The operation of the lever is brought about by the depression of the cross-head 19 which bodily carries the fulcrum 46 of the locking lever downwardly, 10 thus causing its rear extension 45 to engage one of the prongs of the member 44, causing the forward end 48 of the lever to dip downwardly and be projected between a 15 pair of lugs 49 on the printing-wheel. On the upward movement of the plunger, carrying the fulcrum of the locking lever upwardly and likewise the printing-wheel, the rearward extension 45 of the locking lever 20 will engage the opposite prong of the bifurcated member 44, thus causing the forward end 48 of the locking lever to be lifted from coöperation with the lugs 49 so as to release the printing-wheel and enable it to 25 be twirled by the handle 23 when the printing-wheel has reached its uppermost position.

The type-blocks 31 of the printing-wheel are inked in any suitable manner, a means 30 for the purpose being illustrated by dotted lines in Fig. 2, and shown as consisting of a pair of inking rollers 50, carried by the levers 51 pivoted to the plunger 19 and normally drawn together by a spring 52, so as 35 to cause the inking rollers to normally yieldingly engage the printing-wheel.

A variable or adjustable feeding mechanism is also provided, the details of which are made the subject of an application Serial 40 No. 237,966 filed by me of even date herewith; but, herein the feeding mechanism may be generally referred to as consisting of a feed regulating or adjusting lever 53 fulcrumed at 54 to a supporting member 55, the 45 lower end of which lever engages a bifurcated feed-slide 56 carrying a feed-dog 57 at its forward end, said feed-dog being movable independently of the feed-slide to engage the upper surface of the paper and 50 release the same according to the movement of the feed-slide. The spring 58 holds the feed regulating lever 53 normally in the position shown in Fig. 3, and a projection 59 on said lever engages a gage-member 60 55 splined to the spindle 20 and adapted to be rotated therewith, but having no reciprocating movement. The gage-member 60 is provided with a plurality of gage-shoulders or projections adapted to coöperate with the 60 projection 59 of the feed controlling lever, whereby the feed movement of the dog and slide is regulated, all as clearly set forth in my said copending application. A combined stripper and presser for the check, working 65 in coöperation with the printing couple, and

a detent for the check, working in coöperation with the feed-dog to prevent retrieving the check, are part of my machine; but, the same are omitted from the drawings to avoid confusion.

Having thus described the details of my invention, the following mode of operation will be readily understood:

When the check-guides 12 have been properly set for the width of check to be 75 printed, the check will be slid thereinto at the rear of the machine under the tongues 14 and pushed forward until its front end is discernible through the front slot 7 of the frame 2, the feed-dog yielding to the passage 80 of the check. The handle 23 is then twirled to turn the printing-wheel and set the proper type-block in position for coöperation with the platen. The handle 23 is then struck a sharp blow with the hand, thus 85 driving the handle, spindle, plunger and printing-wheel downwardly so that the type-block thereof will engage the check and force the same against the platen. As the printing-wheel goes to functional position, 90 the locking lever is caused to dip its extension 48 between two lugs 49 on the printing-wheel, thus locking the latter from rotary movement. The return of the handle 23, spindle, plunger and printing-wheel, under 95 the expansive force of spring 25, will return all the parts to normal position and will elevate the forward end of the locking lever, thus releasing the printing-wheel and enabling the latter to be rotated again to set 100 the next type-block in functional position. After the printing operation just described has been performed, the feed controlling lever is shifted by the finger toward the handle 23 until the projection 59 of said lever 105 engages a projection or shoulder of the gage-member 60, the latter having been twirled when the printing-wheel was twirled, so as to set the proper feed regulating shoulder in position for coöperation with the projection 59. The lever 53 is then released and the spring 58 will return it to normal position simultaneously driving the feed-slide 56 from back to front of the machine 115 and causing the feed-dog thereof to feed the paper through the machine the required regulated distance for the length of the word printed, plus the space between the same and the next word to be printed. The feed movement, or impulse, thus imparted to the 120 check causes the latter to move toward the operator under his eyes so that he can see what has been printed. This visibility of the printed impression as it is made by the machine is of great practical and commercial 125 importance and advantage.

Having thus described my invention, what I claim and desire to secure by Letters Patent is:

1. A check protecting machine having a 130

- reciprocating plunger, rigid guides carried by the machine frame for confining the plunger to right-line movements, said plunger having a printing-wheel journaled thereon and carrying a locking lever for the printing-wheel, means on the printing wheel enabling the lever to hold the wheel from movement, and means between the machine frame and lever for actuating the latter to engage and lock the printing-wheel.
2. A locking means for printing-wheels for check protecting machines comprising a rigidly set fixture having a bifurcated end, a printing-wheel and means whereby the same may be rotated and reciprocated, a locking lever for coöperation with the printing-wheel having an extension for engagement with the bifurcated fixture, and interacting means between the lever and printing-wheel whereby, when the printing-wheel is driven to functional position, the locking lever will engage the same and prevent it from shifting or rotating.
3. Means for holding a printing-wheel of a check-protecting machine true to its work, comprising a frame having a smooth surfaced plate applied thereto, a printing-wheel having a surface for engagement with said plate, means for supporting said printing-wheel, and means for yieldingly holding the printing-wheel against said plate.
4. A check protecting machine including in combination, a frame, a support for a printing wheel, a printing wheel journaled on said support and adapted to have a limited movement in a direction parallel with the axis of the printing wheel, means for limiting and guiding the movements of the printing wheel, and means for holding the printing wheel in contact with said limiting and guiding means.
5. A check protecting machine including in combination, a frame having a smooth surfaced plate applied thereto, a printing wheel having a surface for engagement with said plate, means for supporting said printing wheel whereby the same may be rotated, and means for holding the printing wheel in contact with said plate whereby said plate determines the printing position of said printing wheel.
6. A check protecting machine having a rotary printing-wheel, the hub of which is hollow, a pointer secured to the hub of the wheel, a hollow supporting member upon which the wheel is journaled, means within the said member normally tending to shift the printing-wheel longitudinally of the supporting member, and means for limiting and guiding the printing wheel.
7. A check protecting machine comprising a printing-wheel, a plunger confined to reciprocating movements, means by which to reciprocate the plunger, and connections between the plunger and the printing-wheel whereby the latter may be rotated and reciprocated, comprising a bevel-gear carried by the plunger, a barrel carried by the plunger, a bevel-gear journaled upon the barrel and adapted to mesh with the first named gear, and the hub of the said second named gear having the printing-wheel secured thereto.
8. A check protecting machine including in combination, a printing wheel, a plunger confined to reciprocating movements, means for reciprocating the plunger, means for supporting said printing wheel on said plunger and for rotating said printing wheel by said plunger comprising a beveled gear carried by the plunger and rotating therewith, a second beveled gear journaled in coöperative relation with the first-named beveled gear and having a hub formed thereon, a printing wheel secured to said hub, and a pointer secured to said hub.
9. A check protecting machine including in combination, a spindle, means for rotating the spindle, a beveled gear carried by said spindle, a bearing, a second beveled gear journaled in coöperative relation with the first-named beveled gear on said bearing, said second beveled gear being mounted on said bearing so as to slide longitudinally thereof, a pointer secured to the hub of said second beveled gear, a printing wheel secured to the hub of said second bevel gear, means carried by the bearing normally tending to shift the printing wheel endwise of the bearing, and means for limiting and guiding said printing wheel.
10. A check protecting machine including in combination, a frame, a plunger mounted to reciprocate vertically in the frame, a printing wheel movable up and down with said plunger and rotated by said plunger, a feeding mechanism including a reciprocating feeding device, a gage for limiting the movement of said reciprocating feeding device, said gage having a fixed relation to the feeding device and having connections with said plunger whereby said gage is rotated with the plunger but is unaffected by the endwise movement of the plunger.
11. A check protecting machine including in combination, a supporting frame, a reciprocating member mounted therein, a plunger for reciprocating said member, a printing wheel mounted on said reciprocating member and having geared connection with the plunger whereby the rotations of the plunger set the printing wheel, a feeding mechanism including a reciprocating device, a gage member for limiting the movements of said reciprocating device, said gage member having a splined connection with said plunger whereby it may be rotated with the plunger but is free from the endwise movements of the plunger.
12. A check protecting machine including

in combination, a frame, a reciprocating member mounted therein, a printing wheel journaled in said member, a gear carried by said printing wheel, a plunger journaled in said reciprocating member, a gear mounted on the plunger and meshing with the gear on the printing wheel and holding the plunger from endwise movements in the reciprocating member whereby said reciprocating

member may be moved up and down by the plunger, a feeding mechanism including a reciprocating feeding device, and a gage member for limiting the movements of the feeding device, said gage member having splined connection with said plunger, and means for holding the gage member from endwise movements with the plunger.

BENJAMIN O. FANSLOW.
